GUILLOTINE CUTTER

Victor William Garwood, London, England, assignor to Moore Business Forms, Inc., Niagara Falls, N. Y., a corporation of Delaware

Application May 24, 1948, Serial No. 28,879
In Great Britain May 5, 1947

4-Claims. (Cl. 164—58)

This invention relates to guillotine cutters particularly but not exclusively adapted for cutting webs of paper or the like and has for its object to provide an improved form of mounting for the movable blade of the cutter whereby the cutting of the web by a combined scissors and slicing action is improved and facilitated.

According to the invention the movable blade of a guillotine cutter is floatably mounted in a carrier and spring means are arranged on the carrier whereby the blade, independently of the carrier, is constantly pressed into contact with the fixed blade of the cutter throughout its length and during the cutting stroke. The spring pressure is distributed substantially evenly and uniformly along the blade length and the blade is moved preferably with a combined downward and horizontal movement.

Other objects and advantages of the invention will be in part pointed out in the following detailed disclosure of an illustrative but preferred embodiment of the invention and will be in part obvious as the disclosure proceeds.

The invention accordingly comprises the features of construction, combination of elements, and arrangement of parts, which will be exemplified in the construction hereinafter set forth and the scope of the application of which will be indicated in the claims.

For a more comprehensive disclosure of the nature, objects and advantages of the invention, reference is had to the following detailed disclosure of the illustrative embodiment thereof, and to the accompanying drawings in which:

Fig. 1 is a front elevation of a guillotine cutter constructed according to one form of the invention, and

Fig. 2 is a plan view of the top blade in its carrier.

Fig. 3 is a sectional view on line 3—3, Fig. 1.

As shown the cutter comprises a fixed blade 4 mounted on a base 5 and a movable blade 6 adapted to co-operate with the fixed blade. The movable blade 6 is fixed by means of screws to a bar 6a of rectangular cross-section which forms the holder and is mounted in a carrier comprising a rigid top bar 7 having bearing pockets 8 one at each end thereof into which the ends of the holder 6a are inserted. The holder 6a is freely movable forwardly or laterally of the top bar 7 in the pockets and two adjustable spring-pressed plungers 9 which bear on its side are mounted on the side of the top bar 7.

Longitudinal movement of the blade 6 and holder 6a is prevented by abutment of the ends of

the blade 6 against the pockets 8 and the holder 6a is limited in its forward movement at one end by a plate 13. An adjusting screw 13a is provided in the plate 13, the end of the screw bearing on the holder 6a so that the forward or lateral movement of the blade 6 towards the fixed blade 4 can be limited as desired. Each plunger 9 is mounted in a cylindrical casing 10 having a cap 11 which acts as an abutment for a coil spring 12, the casing and the cap being screw-threaded so that the cap can be turned to adjust the spring pressure.

The plungers 9 continuously press the blade 6 into contact with the fixed blade 4 during the cutting stroke. More than two spring-pressed plungers 9 may be applied to the blade if desired, preferably equally spaced apart.

The blade carrier is so mounted that one end of the movable blade 6 is always in overlapping contact with the fixed blade 4 as can be seen in Figs. 1 and 3 so that the blades are always in position to start the cutting operation.

The cutter is adapted for hand or power operation and for operative purposes the base 5 is provided with a pivot pin 15 for the carrier 7. One end of the carrier 7 is fitted with a depending lug 16 having a horizontal slot 17 adapted to engage the pin 15 so that the blade 6 can be given a combined downward and longitudinal sliding movement transverse to the base or bed 5 while in contact with the fixed blade 4 to produce a combined slicing and scissors cut. The other end of the carrier 7 is fitted with a depending lug 18 having a slot 19 arranged at an angle and engaging a pin 20 on the base 5 so that when the end of the carrier is depressed the blade 6 will receive a downward movement and also a longitudinal motion depending on the angle of the slot 19. The carrier may be depressed by hand and a return spring (not shown) may be fitted or the carrier may be raised and lowered by mechanical operating means which may be part of a machine with which the cutter is incorporated.

The above described cutter is set up with the end of the movable blade 6 adjacent to the pivot pin 15 always in overlapping contact with the fixed blade 4 under a uniform pressure so that an even scissors-like cut is obtained.

While the arrangement hereinbefore described shows the movable blade of the cutter adapted to be operated to produce a combined slicing and scissors cut it will be understood that the floating blade arrangement is not restricted to any particular form of operation. For example,

the cutter may be set up to produce a true scissors cut the carrier pivoting at one end about a pin on the base, the other end thereof being swung about the pivot to produce the cut by hand or power means.

Since certain changes may be made in the above construction and different embodiments of the invention could be made without departing from the scope thereof, it is intended that all matter contained in the above description or shown in the accompanying drawing shall be interpreted as illustrative and not in a limiting sense.

The invention having thus been fully described, the following is claimed:

1. In a cutter, in combination, a fixed blade and a movable blade, a carrier for said movable blade, said carrier including a rigid top bar having bearing pockets rigidly supported thereon and spaced longitudinally thereof, said movable blade being floatingly mounted in said bearing pockets for adjusting movement independently of said carrier with reference to said fixed blade, spring devices mounted on said top bar and spaced longitudinally thereof and cooperating with said movable blade to yieldingly urge it into contact with said fixed blade throughout the cutting stroke, an adjusting device on each of said spring devices for varying the spring pressure on said movable blade, and an adjustable limiting device on one of said bearing pockets for limiting said adjusting movement of said movable blade.

2. In a cutter, in combination, a fixed blade and a movable blade, a carrier for said movable blade, said carrier including a rigid top bar having bearing pockets rigidly supported thereon and spaced longitudinally thereof, a rigid holder to which said movable blade is firmly attached and the opposite end portions thereof extending into said bearing pockets for floatingly mounting the movable blade for adjustment independently of said carrier with reference to said fixed blade, spring devices mounted on said top bar and spaced longitudinally thereof and having plungers respectively cooperating with said holder to yieldingly urge said movable blade into contact with the fixed blade throughout the cutting stroke, and an adjusting device on each of said spring devices for varying the spring pressure on said movable blade.

3. In a cutter, in combination, a fixed blade and a movable blade, a carrier for said movable blade, said carrier including a rigid top bar having bearing pockets rigidly supported thereon and spaced longitudinally thereof, said movable blade being floatingly mounted in said bearing pockets for adjusting movement independently of said carrier with reference to said fixed blade, spring

devices mounted on said top bar and spaced longitudinally thereof and cooperating with said movable blade to yieldingly urge it into contact with said fixed blade throughout the cutting stroke, an adjusting device on each of said spring devices for varying the spring pressure on said movable blade, an adjustable limiting device on one of said bearing pockets for limiting said adjusting movement of said movable blade, a pin-and-slot mounting support connected to one end portion of said carrier and supporting said movable blade for bodily and pivotal movements, and a downwardly inclined guide at the opposite end portion of said carrier so as to impart a combined slicing and scissors cutting action to the movable blade.

4. In a cutter, in combination, a fixed blade and a movable blade, a carrier for said movable blade, said carrier including a rigid top bar having bearing pockets rigidly supported thereon and spaced longitudinally thereof, a rigid holder to which said movable blade is firmly attached and the opposite end portions thereof extending into said bearing pockets for floatingly mounting the movable blade for adjustment independently of said carrier with reference to said fixed blade, spring devices mounted on said top bar and spaced longitudinally thereof and having plungers respectively cooperating with said holder to yieldingly urge said movable blade into contact with the fixed blade throughout the cutting stroke, an adjusting device on each of said spring devices for varying the spring pressure on said movable blade, a pin-and-slot mounting support connected to one end portion of said carrier and supporting said movable blade for bodily and pivotal movements, and a downwardly inclined guide at the opposite end portion of said carrier so as to impart a combined slicing and scissors cutting action to the movable blade.

VICTOR WILLIAM GARWOOD.
